UNITED STATES PATENT OFFICE.

JOHAN MAYER, OF BRADDOCK, PENNSYLVANIA.

RAIL-JOINT.

No. 894,160.

Specification of Letters Patent.

Patented July 21, 1908.

Application filed December 5, 1907. Serial No. 405,162.

To all whom it may concern:

Be it known that I, JOHAN MAYER, a subject of the King of Hungary, residing at Brad-
dock, in the county of Allegheny and State 5
of Pennsylvania, have invented certain new
and useful Improvements in Rail-Joints, of
which the following is a specification, refer-
ence being had therein to the accompanying
drawing.

10 This invention relates to rail joints, and
the primary object of the invention is, the
provision of positive and reliable means for
connecting the confronting ends of two rails,
without the use of nuts and bolts as ordina-
rily employed in railway construction.

Another object of this invention is to pro-
vide a rail fastener of a simple and durable
construction, that can be easily manipulated
to connect two rails.

20 The invention comprises certain novel
features of construction which will be pres-
ently described, and then specifically pointed
out in the appended claims.

Referring to the drawing, forming a part of
25 this specification, Figure 1 is a perspective
view of a rail joint embodying my invention,
Fig. 2 is a similar view, illustrating the rails as
disconnected, and Fig. 3 is a horizontal sec-
tional view of rails connected in accordance
30 with my invention.

In the accompanying drawings 1 and 2
designate rails having their web portions 3
and 4 respectively, provided with openings 5
and 6. One side of the web 4 of the rail 2 is
35 provided with a splice bar 7, while the oppo-
site side is provided with a resilient clamp 8
having a hook shaped end 9, this hook
shaped end being beveled as at 10. The
splice bar 7 and the clamp 8 are secured to the
40 web 4 by rivets 11, and the splice bar is pro-
vided with a beveled end 12 and also with an
opening 13. The rail 1 is also provided with
a splice bar 14 similar to the splice bar 7
of the rail 2, and a clamp 15 similar to the
45 clamp 8 of the rail 2, but the splice bar is
located upon the opposite side of the rail
from that of the splice bar 7 of the rail 2. By
this arrangement the splice bars 7 and 14
overlap the web portions 3 and 4 of the rails
50 1 and 2 and provide a rigid connection, es-
pecially when the hook shaped ends 9 of the
clamps have entered the openings 13 of the
splice bars 7 and 14 and the openings 5 and 6

of the rails. These hook shaped ends are
adapted to prevent the rails from being acci- 55
dently disconnected, and when joining the
rails together, the beveled hook-shaped ends
9 of said clamps slide over the beveled ends
12 of the splice bars and enter into their re-
spective openings, when said openings have 60
been reached.

When it is desired to disconnect the rails 1
and 2, a suitable instrument such as a chisel
or crow bar (not shown) can be employed to
pry the hook-shaped ends of the clamps out 65
of their openings, and permit of the rails be-
ing disconnected and pulled apart.

It is thought that the many advantages of
my rail joint will be apparent to those skilled
in the art of railway construction. 70

Having now described my invention what
I claim as new, is:—

1. In a rail joint, the combination of rails
having their web portions provided with
openings, a splice bar carried by the web por- 75
tion of each rail, the splice bars upon the rails
being oppositely disposed with respect to
each other and the splice bar of one rail
adapted to overlie the web portion of an ad-
jacent rail, said splice bars having beveled 80
ends and openings adapted to register with
the openings in said web portions, a clamp
carried by each rail opposite the splice bars
of said rails, said clamps having off-set por-
tions terminating in beveled hook-shaped 85
ends for entering the openings of said splice
bars and the openings of the web portions of
said rails, substantially as described.

2. The combination of rails embodying
web portions provided with openings, a 90
splice bar carried by each rail and adapted to
overlap the web portion of the adjoining rail,
each splice bar having an opening formed
therein and extending in the same plane
throughout, a clamp carried by each rail op- 95
posite each splice bar, said clamps having off-
set portions terminating in hook-shaped ends
for entering the openings of said splice bars
and the openings of said rails.

In testimony whereof I affix my signature 100
in the presence of two witnesses.

JOHAN MAYER.
